LAMP FOR ROAD VEHICLES

John Alfred Stevens, Broadstairs, England

Application January 18, 1932, Serial No. 587,356
In Great Britain June 11, 1931

2 Claims. (Cl. 240—41.35)

This invention relates to lamps for road vehicles and has for its object to provide a lamp—particularly a head lamp—which will minimize or eliminate “dazzle” to oncoming vehicles and 5 will not diminish the light projected.

A further object of the invention is to provide a lamp in which the light bulb and its socket will be readily accessible.

The present invention comprises a vehicle lamp 10 having a parabolic reflector wherein is provided a reflector arranged to deflect the upper dazzle producing rays downwards onto the road in front of the lamp.

The upper portion of the lamp is preferably 15 provided with a substantially horizontal opening giving access to the interior of the lamp and provided with a hinged or sliding cover, which when hinged may be hinged to the front edge of the opening at or near the upper edge 20 of the front reflector or to any other suitable portion of the opening.

A manner of carrying out the invention is illustrated by the accompanying drawing wherein Figure 1 is a front elevation, Figure 2 is a sectional elevation and Figure 3 a plan of the improved lamp.

In the drawing *a* is the casing of the lamp, *b* the parabolic reflector and *c* the lamp bulb, all of which may be of any suitable construction.

30 At the front of the lamp is provided a reflector or hood *r*, inclined downwardly from a horizontal front top edge *a1* formed on the casing of the lamp, the lower edge of the reflector being extended downwards sufficiently to cut off 35 all the upper rays which produce dazzle on the driver of an oncoming vehicle, and so that by cutting off such rays the useful rays of the lamp will not be diminished.

The reflector *r* is connected by a hinge *a2* 40 to the front top edge *a* of the lamp and any suitable means may be provided for adjusting the angle of inclination of the reflector.

The surface of the reflector or hood *r* is curved 45 upwards transversely so as to cause rain falling thereon to drain away at the sides of the lamp, and this curvature also causes the downward reflected rays to be inclined in opposite directions so that the portion of the road illuminated by these rays will extend somewhat beyond the 50 sides of the vehicle.

The lamp casing and parabolic reflector are each provided with a horizontal opening at the top thereof which is indicated by the dotted line *a3* and extends to the front edge *a1*, and 55 this opening is provided with a cover *a4* hinged

at the front edge *a1* and provided at its rear edge with a fastening *a5*. The cover *a4* is curved upwards in such a manner as to correspond to the curvature of the parabolic reflector and to cause rain falling thereon to drain away without entering the lamp.

By releasing the fastening *a5* the cover *a4* can be turned about its hinge to give access to the interior of the lamp for cleaning purposes and for the renewal of the lamp bulb *c* when 65 required.

In the preferred construction of the lamp the reflector or hood *r* and cover *a4* are formed in one piece or rigidly connected together and so as to be turnable simultaneously about a common hinge *a2*.

The lamp by reason of the covered horizontal opening will comprise a casing of cylindrical cross section with a top segmental portion removed.

A lamp made in accordance with the present invention can be made of pleasing appearance, and by reason of the top opening is very convenient in use.

I claim:

1. A vehicle lamp comprising a casing, a parabolic reflector mounted in the casing, a lens mounted in the front of the reflector, a hood extending over the front of the lens, and a hinged cover, the upper portion of the reflector being cut away horizontally in a plane parallel to the axis of the lamp and the cover hinged to a hinge extending across the front edge of the cut away portion, the cover also forming a continuation of the hood, and having a flattened curved transverse section of a curvature different from that of the circular section of the parabolic reflector.

2. A vehicle lamp comprising a casing, a parabolic reflector mounted in the casing, a lens 95 mounted in the front of the reflector, a hood extending over the front of the lens, and a hinged cover, the upper portion of the reflector being cut away horizontally in a plane parallel to the axis of the lamp and the cover hinged to a hinge 100 extending across the front edge of the cut away portion, the cover also forming a continuation of the hood, and having a flattened curved transverse section of a curvature different from that of the circular section of the parabolic reflector 105 and of the hood.

JOHN ALFRED STEVENS.
